CAR CONSTRUCTION

David Hindahl, Chicago, Ill., assignor to Harry S.
Hart, Chicago, Ill.

Application September 2, 1933, Serial No. 687,953

7 Claims. (Cl. 105—409)

This invention relates to a new and improved car construction and more particularly to a car wall construction especially adapted for use in connection with cars of the hopper type.

The new and improved car wall construction of this invention produces the combined advantages of maximum capacity and externally positioned side wall stakes and although the invention is intended for application for newly built cars, it is also adapted for application to cars of a type now in existence having inside stakes whereby through the application of this invention to such cars, new and improved wall constructions may be provided without altering the under structure nor the bottom chords of the car, but by merely applying and attaching the newly constructed walls. 5

In cars of the hopper type, the load containing capacity is limited by the clearance diagram of the cars together with the standard height of the top of the hoppers. The hopper walls are constructed of metal plates and in order to provide the requisite strength, the plates are supported by vertically extending stakes located along the side and end walls. The stakes are attached to top and bottom chords which with the stakes constitute the wall frame construction. Heretofore in endeavoring to increase the capacities of cars of this type, some have been built with the stakes mounted inside of the car walls, which enables the placement of the wall plates in the maximum outward position permitted by the limiting dimensions for car width. Such construction however, produces a serious 20 disadvantage in that it exposes the side stakes to wear and damage and deterioration by rust. The material carried in the car wears against the stakes in loading and unloading and the protective painting is worn off which exposes the stakes to the moisture in the load with the resulting deterioration and damage. 25

This objection is very serious because the stakes constitute a vital part of the supporting frame construction and damage thereto constitutes a serious impairment of the strength and serviceability of the car in use. Furthermore, whereas the wall plates can be replaced relatively cheaply and by simple operations, the replacement of the stakes as a part of the car frame is an expensive and more difficult operation. Besides wear and deterioration of the plates do not weaken or impair the supporting frame structure of the car. 30

It will therefore appear that the designers and builders of cars have been confronted with two

conflicting difficulties, the first of which is the objection to less than maximum capacities as occasioned when the stakes are placed on the outside of the walls in order to provide the desired protection for the stakes, and, secondly, the undesirable damage and deterioration of the stakes as a part of the car frame when the stakes are placed on the inside of the car walls so as to afford the maximum capacity produced when the wall plates are positioned approximately at 10 the plane of the outer limiting dimensions of the car. 10

Prior to this invention cars of both types have been constructed and used by the railroads. In those instances where maximum capacity was 15 less important, the stakes were placed externally for the protection benefit but with a considerable sacrifice in load capacity. In recent years, however, increased capacity has become 20 more important with the result that more recent designs provide for outwardly placed walls and internally placed stakes whereby the maintenance and strength of the car frame is sacrificed and damage and deterioration of the stakes is suffered in order to secure the wanted advantage 25 of increased capacity.

The bottom supporting chord of car constructions of this type are usually of angle cross-section having a vertical flange placed in the proper plane to permit the ready attachment thereto 30 of the bottom ends of the wall stakes while at the same time providing a longitudinally extending attachment for the lower edges of the side wall plates. Accordingly, those cars of reduced capacity having outside stakes have been provided 35 with lower chords as a part of their under construction which are placed slightly inwardly of the maximum outside plane of the car so as to abut against the inner surface of the side stakes and serve as an attaching flange for the bottom 40 end of the wall plates. In this case, the bottom frame chords were placed inwardly by the depth of the car stakes. On the other hand, those cars having maximum capacity with the stakes on the inside have been designed with bottom chords 45 placed outwardly so that the vertical flange thereof would abut against the outside surface of the stakes and provide attaching flanges for the side wall plates placed substantially in the plane 50 of the maximum width dimension of the car. 50

Prior to this invention, effort has been made to overcome the problems above presented and to devise a construction for cars which would embody both advantages of capacity and protection 55 so that the stakes could be placed externally to

provide the desirable protection while at the same time, the wall plates could be positioned in the plane of the maximum width of the car so as to provide a maximum capacity. Such construction affords both advantages without the disadvantages previously attending such benefits.

Such a construction is disclosed and claimed in Patent No. 1,623,591, issued April 5, 1927, to Harry S. Hart, the assignee of this application.

10 The disclosure of this patent however, shows and describes a car having an underframe of the type designed for external stakes or in other words, a car having an underframe of the early design as for cars of reduced capacity with wall plates on the inside of the stakes and with lower frame chords disposed inwardly from the plane of maximum permissible width.

By referring to the disclosure of said patent it will be noted that the wall plates are provided at 20 their bottom edges with inturned portions for attachment to the vertical flange of the bottom chord so that a relatively simple and efficient construction is provided with all of the marginal attaching portions of the wall plates disposed in an inner plane to conform to the manner of attaching the inwardly disposed plates of the prior car designs but with their central portions deflected outwardly to occupy a position substantially in the plane of the outer dimension of the car.

However, the teachings of said patent do not readily apply to the type of car having underframes constructed for inside stakes which have their lower chords disposed with their vertical flanges substantially in the plane of the outside dimension of the car. Application of the teachings of said patent to the cars of the type last mentioned involves serious and undesirable alterations at the lower edges of the plates and necessitates undesirable openings or exposure of parts to permit the attachment of the lower edges of the side wall plates to the more widely spaced vertical flanges of the lower chord. If the undesirable openings through the plates are to be avoided, then the lower edges of the stakes at the point of attachment to the lower chord must be exposed to the interior of the car, or if this is to be avoided, then some special expensive and unwanted covering plates or the like, must be provided.

50 Accordingly, the present invention provides a side wall construction which is adapted for application to cars having their lower frame chords more widely spaced than are the chords of the car disclosed in said patent, whereby cars of this type may be built as new cars or the walls hereof may be applied to that type of car having maximum capacity with internal stakes to provide the added advantage of protection of the stakes, without in any wise altering or changing the underframe construction. When this invention is applied to previously existing cars, it is only necessary to remove the old walls and apply the wall construction of this invention which can be immediately attached to the under chord and frame parts from which the old wall was removed. The original gusset plates placed internally of the car are perfectly adapted for attachment to the new wall and if desired, the upper chord can also be used. Furthermore, the new wall construction of this invention is provided with slanting shedding surfaces for all of the internally projecting portions thereof whereby complete and efficient unloading of the car is realized when the car is inverted by unloading apparatus now in common use.

5 In applicant's co-pending application, Serial Number 684,845, filed August 12, 1933, there is shown one form of car construction which is designed to accomplish substantially the same objects of this invention except however, in said co-pending application, the wall plates are placed inwardly of the plane of the maximum permissible side dimension to the extent of the height of rivets and the like, which are necessarily outside of the car wall. This invention therefore, is a modification of the invention of said co-pending application and differs therefrom in that the plates are so constructed as to bring their main portions in the plane of the maximum side dimension with provision for attaching rivets and the like in indentations in the wall surface.

10 The nature of this invention will be better understood by referring to the accompanying drawings, which illustrate, by way of example, one preferred embodiment thereof, and in 15 which;

Figure 1 represents a side elevational view of the body of a hopper car constructed in accordance with this invention;

20 Figure 2 is an enlarged cross sectional view showing a portion of the wall construction and taken on the line A—A of Figure 1 and looking in the direction of the arrows;

25 Figure 3 is an enlarged vertical cross sectional view taken on the line B—B of Figure 1, and looking in the direction of the arrows, and showing the use of standard gusset plates.

30 Figure 4 is a perspective view with portions of the car frame broken away and disclosing the construction of the side wall plate, and

35 Figure 5 is a fragmentary view similar to Figure 4 showing the side stake in cross section in its assembled relationship with the bottom chord and side plate.

40 By referring to the drawings, it will be noted that the bottom chord 11 is in the form of an angle support with the vertical flange thereof positioned in a plane near the maximum outward dimension of the car. The upper chord 12 is of usual construction having a downwardly 45 extending flange 13, disposed inwardly for attachment to the inner surface of the stakes and to provide an attaching flange for the upper edge of the side wall plates which are disposed inwardly as clearly illustrated in Figure 3. 50

55 Side wall plates 14 may be of any suitable width depending upon the desired construction of the car and as here illustrated, the three end plates are of less width than the central plates. It is preferable, but not necessary, that each of the plates be of sufficient width to occupy the space between stakes and therefore the width of the plates may be selected according to the number and spacing of the stakes required for the desired frame construction. Each of the 60 plates has a top flange 15 disposed in the inner plane and side flanges 16 and 17 respectively, also disposed in the inner plane and which are made continuous with the main panel or panels 18, of the wall plate by off-setting surfaces 19 and 20, preferably inclined, as shown. It is highly desirable to have the upper surface 20 inclined so as to provide the necessary shedding action when the car is inverted in the usual unloading operation.

70 The lower edge 21 of the plate is disposed in a plane outwardly of the plane of the flanges 15, 16, and 17 and near the plane of the maximum width dimension of the car so that it is disposed in proper position for attachment to the 75

vertical flange of the bottom chord 11. The lower edge 21 however, is disposed slightly inwardly of the plane of the side wall panels 18. Side flanges 16 and 17 are inclined outwardly 5 at their lower portions as at 22 and 23, respectively, so as to join continuously with the lower edge 21 of the plate. The main panels 18 also join continuously with the lower edge 21 through the inclined portions 36.

As illustrated in Figure 2, the plates are adapted to be placed side by side, to form the continuous wall of the car and are preferably mounted with their side flanges 16 and 17 in overlapping relation and attached by suitable means, such as rivets 24, to the vertical stakes 25.

The stakes of this invention are preferably constructed in the manner illustrated in the drawings so as to comprise an angle support having a flange 26 in the inner plane for the attachment 20 of the wall plates and the flange 13 of the upper chord 12, and an outwardly extending flange 27 which terminates in the plane of the maximum permissible dimension of the car. It will be noted 25 that the flange 27 extends slightly beyond the plane of the lower edge 21 but even with the main panel or panels 18 of the wall plates.

At the lower portion of the stake, the flange 26 is inclined outwardly as at 28 so as to terminate at 29 in an outer plane for external attachment 30 to the vertical flange of the lower chord 11. The outer edge of the outwardly extending flange 27 preferably continues straight downwardly so as to provide a reinforcement 30 for the portion 29 of the stake. In order to provide additional 35 strength, an enlargement 32 may be provided along the edge of the flange 27 throughout the central and upper portion thereof.

As shown in Figures 3, 4, and 5, the inner plate 33 which is now utilized in the standard car 40 constructions of the type herein referred to, may be retained exactly as before, so as to provide a shedding surface and a covering and protecting plate for the lower chord 17. The upper edge of the vertical flange of the lower chord 11, 45 may be covered by extending the plate 33 or it may be protected by paint or other material applied thereto. This narrow edge can be readily protected in practice so as to avoid exposure of the frame parts to the load in the car.

As shown in Figures 1, 2, and 4, this invention 50 differs from the invention of applicant's co-pending application referred to, in that the main portion of the side plates, that is to say, the panels 18, are disposed in the plane of the maximum permissible width dimension of the car so that 55 the panels 18 extend outwardly to a small extent beyond the plane of the bottom edge 21. Those plates located adjacent the central region 60 of the car and to which the gusset plates shown in Figure 3 are attached, are provided at their central portion with a vertically disposed indentation 35, the surface of which is in the same plane as the bottom edge 21. The difference 65 between the plane of the bottom edge 21 or the vertical indentation 35 and the plane of the outer panels 18 of the plate is just that of the height of the heads of the rivets required for attaching the gusset and similar parts to the plates. This is clearly illustrated in Figure 3.

Accordingly, this invention increases the capacity 70 of the car to some extent beyond the capacity of the car illustrated in said co-pending application, as it provides side plates, the major portion of which are actually in the plane of the maximum width dimension. At the same time, the

bottom edge is so constructed as to be disposed in an outer plane properly located for attachment to the bottom chord 11 while the top and side flanges 15, 16, and 17, are disposed inwardly for attachment to the inner surface of the side stakes and the depending flange 13 of the upper chord 12.

From the above construction, it will be noted 5 that a car of substantially maximum capacity is provided by virtue of the fact that the wall plates are for the most part, disposed in the plane of the maximum width of the car while at the same time, the side wall stakes are exterior of the plates and are thereby entirely protected from the contents of the car and damage 10 and deterioration occasioned when the stakes are placed internally.

Furthermore, this invention differs from the 15 invention illustrated in Patent No. 1,623,591, above referred to, in that it is particularly adapted for the type of car having more widely spaced lower chords, so that the side wall plates have a bottom edge in an outward plane for 20 attachment to the upward flange of the lower chords and so as to afford a simple and efficient 25 construction with the stakes disposed externally of the wall.

It will readily appear from Figure 3 that the 30 wall construction here provided is adapted to be supported with the standard gusset plates now employed in the type of car having external stakes and outwardly placed wall plates whereby it is only necessary in converting standard cars, to remove the old wall and attach the new wall 35 construction. In building new cars no alteration is necessary in the frame construction, gusset plates, and like standard parts as the wall lends itself perfectly to application to standard car constructions of the type referred to.

I claim:

1. A wall plate for railway cars having top and side marginal portions disposed in an inward plane and a central main portion disposed in a parallel outward plane and a bottom marginal portion disposed in a plane parallel to but intermediate said first two planes, inclined 45 marginal portions joining said side and bottom marginal portions and other portions joining said central main portion and said top, bottom and side marginal portions respectively.

2. A railway car of the character described 50 having in combination a frame comprising upper and lower chords and side stakes connected between said chords, said upper chord having a wall plate attaching flange disposed in an inward vertical plane, said lower chord having a wall plate attaching flange disposed in an intermediate plane located outwardly of said first-named plane, and said stakes having wall plate 55 attaching portions disposed in said inward plane and inclined portions extending from said inward plane to said intermediate plane; and a wall plate for said frame having top and side marginal portions disposed in said inward plane and attached to said upper chord flange and said inwardly disposed portions of said side stakes 60 respectively, and a central main portion disposed in an outward plane located outwardly of said intermediate plane, said wall plate also having a bottom marginal portion disposed in said intermediate plane and attached to said bottom chord flange, and inclined marginal portions 65 joining said side and bottom marginal portions and attached to said inclined portions of said side stakes, said wall plate further having other 70

75

portions connecting said main portion with said top, bottom, and side marginal portions respectively.

3. A railway car of the character described having in combination a frame comprising upper and lower chords and side stakes connected between said chords, said upper chord having a wall plate attaching flange disposed in an inward vertical plane, said lower chord having a wall plate attaching flange disposed in an intermediate plane located outwardly of said first-named plane, and said stakes having wall plate attaching portions disposed in said inward plane and inclined portions extending from said inward plane to said intermediate plane; and a wall plate for said frame having top and side marginal portions disposed in said inward plane and attached to said upper chord flange and said inwardly disposed portions of said side stakes respectively, and a central main portion disposed in an outward plane located outwardly of said intermediate plane, said wall plate also having a bottom marginal portion disposed in said intermediate plane and attached to said bottom chord flange, and inclined marginal portions joining said side and bottom marginal portions and attached to said inclined portions of said side stakes, said wall plate further having intermediate portions joining said top, bottom and side marginal portions, and said wall plate further having a central portion disposed in said intermediate plane and positioned to accommodate rivets for holding said wall plate to said frame.

4. A railway car of the character described having in combination a frame comprising upper and lower chords and side stakes connected between said chords, said upper chord having a wall plate attaching flange disposed in an inward vertical plane, said lower chord having a wall plate attaching flange disposed in an intermediate plane located outwardly of said first-named plane, and said stakes having wall plate attaching portions disposed in said inward plane and inclined portions extending from said inward plane to said intermediate plane; and a wall plate for said frame having top and side marginal portions disposed in said inward plane and attached to said upper chord flange and said inwardly disposed portions of said side stakes respectively, and a central main portion disposed in an outward plane located outwardly of said intermediate plane, said wall plate also having a bottom marginal portion disposed in said intermediate

plane and attached to said bottom chord flange, and inclined marginal portions joining said side and bottom marginal portions and attached to said inclined portions of said side stakes, said wall plate further having intermediate portions joining said top, bottom and side marginal portions, and said wall plate further having a central portion disposed in said intermediate plane and positioned to accommodate rivets for holding said wall plate to said frame.

5. A wall plate for railway cars having portions disposed in inward, outward, and intermediate parallel planes, the top and side marginal portions being disposed in said inward plane, the bottom marginal portion being disposed in said intermediate plane, and the main central portion being disposed in said outward plane, said wall plate also having portions joining said central main portion and said marginal portions.

6. A wall plate for railway cars having portions disposed in inward, outward, and intermediate parallel planes, the top and side marginal portions being disposed in said inward plane, the bottom marginal portion being disposed in said intermediate plane, and the main central portion being disposed in said outward plane, said wall plate also having inclined portions joining said central main portion with said top and bottom marginal portions respectively, and other portions joining said central main portion and said side marginal portions.

7. A frame and wall plate construction for railway cars comprising an upper chord having a portion disposed in an inward plane, a wall plate having a main central portion disposed in an outward plane, a lower chord member having a portion disposed in an intermediate plane, and side stakes connected between said upper and lower chords, said wall plate also having a top marginal portion connected to said upper chord in said inward plane, a bottom marginal portion connected to said bottom chord in said intermediate plane, side marginal portions connected to said side stakes, and central inclined portions connecting said central main portion and said top and bottom marginal portions respectively, and other portions connecting said central main portion and said side marginal portions.

DAVID HINDAHL.
